FIG. 5.

UNITED STATES PATENT OFFICE.

EMIL HUBER, OF CHESTER, PENNSYLVANIA.

MACHINE FOR STRAIGHTENING THE WEFT-THREADS OF TEXTILE PIECE GOODS.

1,387,155.

Specification of Letters Patent.

Patented Aug. 9, 1921.

Application filed March 12, 1920. Serial No. 365,199.

To all whom it may concern:

Be it known that I, EMIL HUBER, a citizen of the United States, residing at Chester, in the county of Delaware and State of Pennsylvania, have invented certain new and useful Improvements in Machines for Straightening the Weft-Threads of Textile Piece Goods, of which the following is a specification.

10 This invention relates to an improvement in the machine described and claimed in my Patent No. 1,326,057 granted December 23, 1919, on a machine for straightening the weft threads of textile piece goods.

15 More particularly it relates to a construction allowing the movement of each of the roll bearings to any desired position so that the rollers may be adjusted to any desired angle or position with relation to each other.

20 My former machine permitted the horizontal movement of one of the bearings of one of the rolls while the other bearing was allowed to swivel; also one of the bearings of the other roll was capable of vertical ad-

25 justment while its other bearing swiveled. It has been found in practice that it is often desirable to change the relative positions of the rollers and their angles with each other to a greater extent than was possible

30 with the old machine. With this idea in view, it was conceived that by having all the bearings of all the rollers capable of universal adjustment, that more delicate and accurate set of the rollers for any particular

35 piece of work could be obtained.

An object of my invention is to accomplish the accurate adjustment of the rollers to any desired angle or position so that my machine may be adapted to successfully perform its functions under all conditions of use.

Another object of my invention is to provide a machine in which the construction is simple and light and yet combines great strength, with the additional feature that it may be attached to any convenient overhead structure such as is commonly used in cloth handling machinery.

With these and other objects in view which may be incident to the improvements, my invention consists in the parts and combinations to be hereinafter set forth and claimed, with the understanding that the several necessary elements comprising my invention may be varied in their proportions and arrangement without departing

from the spirit and scope of the appended claims.

In order to make my invention more clearly understood, I have shown in the accompanying drawings, means for carrying it into practical effect without limiting the improvements in their useful applications to the particular constructions, which for the purpose of explanation have been made 65 the subject of illustration.

Figure 1 is a side elevation of one form of a weft tendering mechanism embodying my invention. Fig. 2 is a top view of the weft tendering mechanism shown in Fig. 1. Fig. 3 is an end elevation of the form of weft tendering mechanism shown in Fig. 1. Fig. 4 is a detail partly in elevation and partly in cross section of the swiveled bearing and means for movement of the same. Fig. 5 is 75 a detail partly in elevation and partly in cross section of the mechanism for moving the swiveled bearing both vertically and horizontally. Fig. 6 is a cross sectional view taken through line 6—6 of Fig. 5. 80

The frame for supporting the rolls consists of side bars 1 and 2 formed preferably of angle iron. Through the upper side of an angle iron are drilled holes 3 whereby the side bars 1 and 2 will be screwed, bolted or riveted to any convenient supporting structure. Bolted to the downwardly projecting flange of side bars 1 and 2 are struts 5 and 6 and 7 and 8 respectively. To one end of the side bar 1 and to the end of strut 6, that 90 is not bolted to the side bar 1, is bolted an upright 9. Correspondingly at the other end of the side bar 1 and the free end of strut 5 is bolted an upright 10. Likewise to the side bar 2 and to the strut 7 is bolted 95 an upright 11, and to the side bar 2 and the strut 8 is bolted an upright 12. Uprights 9 and 11 are horizontally connected by guide bars 13 and 14 which are suitably bolted therethrough. The guide bars 13 and 14 100 are of square rolled steel and not only serve the purpose of forming a strong frame structure but act as guides for the movable structure supporting the rollers to be later described. The uprights 10 and 12 are also 105 connected by guide bars 15 and 16 which serve the same purpose and perform the same functions as has previously been explained in regard to guide bars 13 and 14.

Upon guide bars 13 and 14 and 15 and 16 110 are adapted to slide reciprocating supports 16'. These reciprocating supports are

formed with square apertures of larger dimensions than the square guide bars. To form a close fit between the reciprocating supports 16' and the guide bars, the supports are put in place and Babbitt metal 17 is poured around the guide bars and forms a bearing surface. It will be apparent to those skilled in mechanical matters that there is a great saving in labor and cost by 10 reason of this peculiar method of forming the bearing surface. To make a square aperture of the correct dimensions and close fit through the hard metal of the members 16' would be a very expensive undertaking. 15 However, by making the aperture through 16' larger than is necessary and pouring in Babbitt metal, an accurate and efficient bearing is made at small cost. Likewise the reciprocating supports 16' are adapted to be 20 driven by a traveling screw later to be described and where they have their surfaces of contact with the traveling screw, Babbitt metal is again employed as indicated at 18. A screw is set in place with either right or 25 left hand threads and Babbitt metal is poured around the same. The surface of contact of this Babbitt metal 18 with the traveling screw is less than half a circumference of a circle. This bearing metal is re- 30 tained in place and prevented from slipping by having the hard metal of the member 16' slightly indented or reamed out as indicated at 18'. The hot babbitt flows into these recesses and upon cooling the bearing surface 35 is locked firmly in place.

As clearly shown in Fig. 3, the support 16' is formed with supporting webs 19 (see Fig. 6 for detail of cross section). The purpose of these webs is to give added strength 40 and rigidity to the member 16' and to equalize the strains to which it is subjected. Through the center of the member 16' is bored a cylindrical hole from its top down to a point just above the Babbitt metal 17. 45 Because of the size of the cylindrical hole and the configuration of the reciprocating support, there is left an air space as indicated in Figs. 3 and 5. The walls 20 of this cylinder are adapted to serve as guides. At 50 the top of the support 16' is a screw support 21 firmly bolted in place. Within the cylindrical guides 20 is adapted to reciprocate a cylindrical plunger 22 provided at its top with a screw threaded aperture 23 into 55 which is screwed a screw 24. The screw 24 is adapted to be fastened in place by any of the well known systems such as by putting sal-ammoniac on the threads and allowing them to rust tight or by drilling through 60 plunger 22 and screw 24 and inserting pin. At the other end of the screw 24 is a bushing 25 screw threaded to accommodate the convolutions of the screw 24. This bushing 25 is provided with an annular flange 26 as indicated in Fig. 5. A

hand wheel 27 is keyed to the bushing 25 by means of a key 28. In the case of the upper rolls, the bushing 28 lies above the plate 21 and the hand wheel so that the collar 26 takes the downward strain and supports the 70 screw 24. In the case of the lower rolls, the collar 26 is similarly locked to turn integrally with the hand wheel but is located above the plate 21 so that it may bear a downward pressure. 75

The cylinder 22 is bored out to form a shell as indicated at 29' and a seat 29 of conical cross-section corresponding to the shape of the bit. Within the shell 29' and at its lower end (see Fig. 4) there is provided an annular plate 30 which closely fits the interior of the cylinder 29' and is keyed in place by a pin 31. Shafts 32 which support the rolls A and B are provided near their extremities with a sphere 33 adapted to fit within the interior of the cylinder 29' and forming a universal joint. The bearing surfaces are formed by the plate 30 and the conical bearing surface 29. Through the cylinder 29' are drilled holes 34 passing from 90 one side through to the other and through which are adapted to pass the shafts 32. The size of the apertures 34 is such that the rolls may be rotated to any convenient desired angle as indicated in dotted lines in 95 Fig. 4.

Passing through the uprights 9 and 10 and 11 and 12, parallel to and midway between the guide bars are shafts 35 carrying over a portion of their length 2-way screws 100 36 which are adapted to be turned by means of convenient hand wheels 37. Bearing against the screw threads and in engagement therewith are the bearing surfaces 18 previously described. It is to be understood 105 that the bearing surfaces 18 in the case of the upper rolls are adapted to engage with the right hand screw threads, whereas those of the lower rolls are adapted to engage with the left hand screw threads or vice-versa. 110

By means of hand wheels 37 the reciprocating supports 16' may be made to assume any desired position upon the guide bars. It will be understood that the upper reciprocating support moves in one direction while the lower one is moved in an opposite direction so that the rolls may be made to assume any of the positions shown in dotted lines in Fig. 3. That is to say the rolls may be directly one above another or may be at the extreme opposite positions permitted by the length of the screw thread 36 and the construction of the machine. Likewise the ends of the rolls may be raised or lowered at 125 will by operating the hand wheels 27 which by turning bushings 26 raise or lower the pistons 22 that carry with them the ball and socket joints in which turn the shafts 32 of the rollers A and B. 130

Because of the angular shape of the guide bars 13 and 14 and 15 and 16, the reciprocating supports 16' are held in their positions and may be subject to considerable strain without suffering displacement. Likewise by reason of web supports 19, the plates 21 upon which comes the greater portion of the strain of supporting the rollers are held very steady. It will be apparent to those skilled in the art that a very compact and strong construction is achieved by my invention. There is small danger of distortion due to normal strain and there will be but little vibration because of the sturdy construction of the frame and the reciprocating supports. Any desired angle between the rollers or any desired position of the rollers may be obtained in my machine. The bearings of the shafts of each of the rollers are movable at their ends to any desired position within the plane of the reciprocating supports hence a very efficient and extremely flexible adjustment is achieved. My machine will, because of its adaptability to any conditions of ordinary use, increase the number of "firsts" and decrease the number of "seconds" and will perform the labor usually performed by several skilled workers.

30 While I have described but one embodiment of my invention it is apparent that many modifications may be made thereunder by those skilled in the art without departing from the spirit thereof and I desire therefore that my invention be limited only as set forth in the appended claims or by the showing of the prior art.

I claim:

1. In a fabric tentering or stretching machine, the combination of rolls, with means for effecting angular adjustment between the rolls in all planes.
2. In a fabric tentering or stretching machine, the combination of rolls, with means for effecting angular adjustment of the rolls in one plane, and combined right and left hand threaded screws for effecting adjustment in other planes.
3. In a fabric tentering or stretching machine, the combination of rolls with screws for each end of each roll, and hand wheels coöperating with the screws to move the end of the rolls.
4. In a fabric tentering or stretching machine, the combination of rolls with a screw for each end of each roll, hand wheels coöperating with the screws to move the ends of the rolls to adjust them angularly in one plane, and means for effecting angular adjustment in other planes.
5. In a fabric tentering or stretching machine, the combination of rolls, with means for effecting angular adjustment of the rolls in one plane comprising a screw for each end of each roll, hand wheels, and bushings

on the hand wheels engaging the screws to move the ends of the rolls.

6. In a fabric tentering or stretching machine, the combination of rolls, with screws for each end of each roll, hand wheels, bushings on the hand wheels engaging the screws to move the ends of the rolls, and other means for effecting angular adjustment of the rolls.

7. In a fabric tentering or stretching machine, the combination of rolls with screws for each end of each roll, hand wheels, bushings on the hand wheels engaging the screws to move the ends of the rolls, keys coöperating with the bushings and hand wheels to cause them to rotate integrally and further means for effecting angular adjustment between the rolls.

8. In a fabric tentering or stretching machine, the combination of rolls, with supports, screws for each end of each roll, hand wheels, bushings on the hand wheels engaging the screws to move the ends of the rolls, keys coöperating with the bushings and hand wheel to cause them to rotate integrally, and collars on the bushings adapted to transmit the strain on the screw to the supports.

9. In a fabric tentering or stretching machine, the combination of rolls, with means for effecting angular adjustment of the rolls in one plane, supports for said means, bars of angular cross section upon which the side members of the frame are adapted to slide, and means for effecting angular adjustment of the rolls in other planes.

10. In a fabric tentering or stretching machine, the combination of rolls, with means for effecting the angular adjustment of the rolls in one plane, and combined right hand and left hand threaded screws for effecting adjustment in other planes.

11. In a fabric tentering or stretching machine, the combination of rolls, with means for effecting angular adjustment of the rolls in one plane, supports for supporting the above mentioned means, combined right hand and left hand threaded screws for effecting adjustment in other planes, right hand threaded surfaces on half the above mentioned supports, left hand threaded surfaces on the rest of the supports, the threaded surfaces being so arranged that they may travel past each other on the same screw.

12. In a fabric tentering or stretching machine, the combination of rolls with universal bearings for the rolls capable of limited universal adjustment, means for effecting angular adjustment in one plane and means for effecting angular adjustment in other planes.

13. In a fabric tentering or stretching machine, the combination of rolls, with means for effecting angular adjustment of the rolls in one plane and combined right and left hand threaded screws for effecting adjust-

- ment in other planes, and hand wheels whereby the screws may be rotated.
14. In a fabric tentering or stretching machine, the combination with the guide bars forming part of the frame thereof, of rolls, means for effecting angular adjustment of the rolls in one plane and means for effecting angular adjustment of the rolls in other planes.
- 10 15. In a fabric tentering or stretching machine, the combination with the frame thereof, struts fastened at one end to the side bars of the frame and guide bars attached to the struts, of rolls, means for effecting angular adjustment of the rolls in one plane

and combined right and left hand screw threaded screws for effecting adjustment in other planes, and hand wheels whereby the screws may be rotated.

16. In a fabric tentering and stretching machine, the combination with the side bars of the frame, struts fastened at one end to the side bars and guide bars attached to the strut, or rolls, means for effecting angular adjustment of the rolls in one plane and 25 means for effecting angular adjustment of the rolls in other planes.

In testimony whereof I affix my signature.

EMIL HUBER.
